(57) **CLAIM**

The ornamental design for a roof rake, as shown and described.

DESCRIPTION

FIG. 1 is perspective view of the roof rake showing my new design;

FIG. 2 is a left side view thereof;

FIG. 3 is a right side view thereof;

FIG. 4 is a front view thereof;

FIG. 5 is a back view thereof;

FIG. 6 is a top view thereof;

FIG. 7 is a bottom view thereof;

FIG. 8 is a perspective view thereof with a handle shown in a retracted position in broken lines; and,

FIG. 9 is a perspective view thereof with a handle shown in a deployed position in broken lines.

The broken line showing of the handle and slide illustrates the environment of the claimed design and forms no part thereof. The remaining broken lines in the drawings illustrate portions of the roof rake and form no part of the claimed design.
